UNITED STATES PATENT OFFICE.

HARRY GEORGE LANCASHIRE, OF WINNIPEG, MANITOBA, CANADA.

SHOCKING-MACHINE.

1,246,951.

Specification of Letters Patent. Patented Nov. 20, 1917.

Application filed September 27, 1916. Serial No. 122,535.

To all whom it may concern:

Be it known that I, HARRY GEORGE LANCASHIRE, of the city of Winnipeg, in the Province of Manitoba, Canada, have invented certain new and useful Improvements in Shocking-Machines, of which the following is the specification.

The invention relates to improvements in shocking machine, and the principal object of the invention is to provide a machine which can be readily attached to the side of a binder and which when attached will receive the sheaves delivered from the deck, elevate them and discharge them into a receiving basket wherein they are formed into a shock and after being compressed to spread the base of the shock are dumped on the ground butts down by the turning of the basket, which is directly controlled from the binder. A further object of the invention is to provide in a machine of this class an elevator provided with specially constructed fingers which will catch and carry the sheaves without jarring them unduly and further, an elevator controlled to accommodate the oncoming sheaves from the deck when the basket is dumped. A still further object of the invention is to provide a basket having compression arms adjustable in respect to the basket and arranged in the open position to act as guides for the sheaves passed into the basket and further, to provide piercing prongs in the bottom of the basket which co-act with the compression arms to retain the shock in the basket when the same is being turned to dumping position. A still further object of the invention is to provide in a machine of this type a means for cushioning or taking the jar off the basket when the same returns to the original position after having been dumped.

With the above objects in view the invention consists essentially in the arrangement and construction of parts hereinafter more particularly described and later pointed out in the appended claims, reference being had to the accompanying drawings in which:

Figure 1 represents a plan view of my shocking machine attached to a binding machine with the deck extension removed.

Fig. 2 represents a rear end view of the parts appearing in Fig. 1.

Fig. 3 is a side view of the shocking machine from the outer side.

Fig. 4 is an enlarged detailed side view of

one of the basket clutches and adjacent parts.

Fig. 5 is a face view of the parts appearing in Fig. 4.

Fig. 6 is a side view of a portion of the basket showing one of the compression arms and adjacent parts.

Fig. 7 is an enlarged detailed vertical sectional view through the spring box secured to the basket and contained parts, together with the associated bracket carried by the shocker frame.

Fig. 8 is an enlarged detailed plan view of one of the fingers and cross slats supporting the same.

Fig. 9 is a side view of the parts appearing in Fig. 8.

Fig. 10 represents a side view of the controlling rod and parts controlled thereby.

Fig. 11 is an enlarged detailed vertical sectional view through the elevator controlling clutch.

In the drawings like characters of reference indicate corresponding parts in each figure.

1 represents the main frame of a binding machine and 2 the deck thereof over which the sheaves bound by the binder are customarily delivered.

3 represents the pitman shaft of the binder which is located in the usual position and is driven by the binder driving chain 4.

I have not considered it necessary to enlarge further upon the construction or arrangement of these parts nor to disclose herein further parts of the binder as these are considered too well known to receive detailed description.

5 and 6 represent a pair of outstanding hangers permanently secured at 7 to the binder frame and forming supports for the inner ends of a pair of side bars 8 and 9, which side bars are pivotally secured to the hangers as indicated at 10.

The outer ends of the side bars are secured permanently at 11 to the shocking machine frame 12, which frame is in reality a substantially open ended rectangular one formed from upper and lower parts presenting upper side members 13 and 13', lower side members 14 and 14', connecting upper and lower front cross members 15 and 15' and connecting end portions 16 and 16'.

17 and 18 are oppositely disposed more or less U-shaped wheel supports having their inner sides permanently secured respectively.

to the members 13 and 14 and 13' and 14' of the frame and carrying short axles 19 and 20 on which are mounted carriage wheels 21 and 22 fitted with chain wheels 23 and 24. 5 These wheels support the rear part of the machine while the front part thereof is carried by a caster wheel 25 located at the lower end of a forked shank 26 swivelly secured in carrying brackets 27 permanently 10 secured centrally to the cross members 15 and 15' of the shocker frame.

The upper members 13 and 13' of the shocker frame are supplied with a pair of opposing bearings 28 and 29 which actually 15 carry the sheaf receiving and shock forming basket now described.

The basket 30 is an open topped one and is formed from sheet metal shaped to present a contracted rear end and an enlarged front 20 end, this flaring construction initially effecting the shaping of the shock. Reinforcing side bars 31 and 32 are secured to the upper edges of the basket and it is braced further by an applied reinforcing band 33 25 passing around it on the underside.

34 and 35 are alined basket supporting shafts having their inner ends permanently secured by castings 36 to the opposite sides of the basket.

30 The extending ends of the basket shafts protrude through the bearings 28 and 29 and they are received within sleeves 37 rotatably mounted on the shafts and in the bearings 35 and provided at their outer ends with chain wheels 38 and 39 and at their inner ends with male clutch members 40. The male clutch members are associated with female clutch members 41 feathered on the respective basket shafts as indicated at 42, and 40 these female clutch members are controlled from the binder in a manner later disclosed. For the sake of brevity I will hereinafter refer to these clutch members as A and B.

The chain wheels 38 and 39 are connected 45 with the driving chain wheels 23 and 24 by chains 43 and 44.

From the above construction it will be obvious that if the clutch members A and B should be disengaged the carriage wheels 21 50 and 22 will continuously operate the sleeves and will produce no movement in the basket, this not taking place until the clutch members are engaged.

45 and 46 are a pair of compression arms 55 having their lower ends protruding through slots 47 provided in the sides of the basket and pivotally secured by a bolt 48 to lugs 49 located on the outer sides of the basket. It will be here noticed that there are a number 60 of lugs which allow one to adjust the compression arms by removing the bolts and reinserting them in a different pair of lugs.

The upper end of the compression arms are bent outwardly in a more or less semi-65 circular manner as best shown in Fig. 2,

and by being so bent they provide guides for the sheaves thrown to the basket. Each compression arm is controlled by a somewhat S-shaped operating bar 50 which has the upper end thereof fastened to the compression arm by a pin 51 entering a slot 52 in the arm, the body portion thereof passing to the outside of the basket and the lower end thereof adjustably fastened as by a set screw 50* to a short, normally horizontally disposed spindle 53 having the ends thereof carried in bearing brackets 54 and 55 secured to the opposite sides of the basket. The peculiar bend in the bars is provided so that upon the spindles being turned the upper ends of the bars can swing in over the top of the basket and throw down the compressor arms. Each of the spindles 53 is controlled in its movement by an outstanding lever 56 fitted with a 85 roller 57 which operates on a cam track 58 suitably suspended by brace bars 59 and 60 from the shocker frame and wheel supports. The two cam tracks (one at each side of the basket) are similar in construction and are 90 bent into the shape best shown in Fig. 3 of the drawings, where one of them appears in side view. Here it will be observed that normally the roller is pocketed in the lower portion of the track and that the track extends upwardly for a short distance at only a slight angle to the vertical as indicated at 58', then is bent concentric to the basket shaft as indicated at 58² and finally passes away gradually as indicated at 58* from the basket shaft and terminates in a stop 58². This peculiar arrangement of the cam tracks is such that when the shaft is swung in the 95 turning of the basket in the direction indicated by the arrow, Fig. 3, the rollers will operate to swing the compression arms quickly down, this occurring during the interval that the rollers are passing over the parts 58' of the tracks, will then retain for a short period the compression arms in the swung down position, this occurring during the interval that the rollers are operating on the concentric parts 58², and will then swing away from the basket shafts 100 while operating on the parts 58* of the tracks and by so doing will release the compression arms. Obviously, by so controlling the compression arms the head of the shock will be initially compressed in the basket to spread the butt. The shock will be held in the basket during the upending thereof and will be free to drop at a proper instant to clear from the basket. The final dumped position of the basket is limited by the rollers striking the stops 58².

105 In addition to the compression arms for holding the shock in the basket, I have provided piercing prongs 61 and 62 which protrude through the underside of the basket and are carried by rocker bars 63 110

and 64 pivotally attached at 65 to the basket and having their upper ends offset outwardly at 63' and 64' and directly under the control of inserted spiral springs 66 and 67. As will be observed, the prongs are held projecting into the basket by the action of the springs, with the result that the shock is restrained from sliding in the basket by the prongs until such time that 10 the prongs are withdrawn and this is accomplished by providing striking plates 68 and 69 secured to the cam tracks which are designed, when the basket dumps, to hit and press in the ends 63' and 64' of the 15 rocker bars.

The front end of the basket carries at the opposite sides a permanently mounted spring box 70 in which is mounted slidably a normally vertically disposed striker rod 20 71 fitted with a collar 72 and directly under the control of a compression spring 73 inserted between the collar and the base of the box. The ends of the rods project beyond the box and the upper ends thereof 25 are designed in the normal or sheaf receiving position of the basket to ride against the undersides of brackets 74 permanently secured to the shocker frame. This latter arrangement is such that when the basket 30 is returned to the original position after dumping it is cushioned by the upper ends of the rods striking the undersides of the brackets.

Between the basket and the deck I have 35 located an elevator 75 which is driven from the binder and is arranged to receive sheaves delivered from the deck, elevate them and deposit them in the basket. This elevator is now described in detail.

40 76 is a lower conveyer cross shaft rotatably mounted in the side bars 8 and 9 and 77 and 78 represent the side frames of the elevator which have their lower ends mounted on the shaft 76 and their upper ends 45 carried by side braces 79 and 79' extending from the bars 8 and 9. The upper ends of the elevator frames carry a top cross shaft 80 which is adjustably mounted in any suitable manner in the side frames. The cross 50 shafts 76 and 80 are fitted with pairs of chain wheels 81 connected by driving chains 82 and they are supplied further, between the said frames, with rollers 83 on which I have mounted endless bands or straps 84.

55 85 and 85' are pairs of cross slats fastened to the straps and also to the chains and disposed a suitable distance apart. Each pair of slats carries a set of extending fingers 86 which fingers are of the special construction 60 now described.

Each finger comprises a main rod 87 having one end slightly hooked as shown at 87' and the other end formed into a more or less rectangular loop 87' which is pivotally 65 mounted in a bearing strap 88 secured to

one of the slats, the looped end of the rod being bent backwardly at an angle to the body thereof.

87' is a second rod bent into a loop more or less in the nature of an open ended link 76 and having the ends thereof pivotally secured by means of a pin 89 to the rod 87 and the body portion thereof fastened pivotally to the other of the slats by a bearing strap 89'. By so constructing the fingers 75 and connecting them to the slats, it will be seen that I form a specially good carrier for the sheaves deposited from the deck and also provide a simple arrangement which allows the fingers to travel readily around 80 the rollers.

Between the lower end of the deck and the lower end of the conveyer I locate a deck extension board 90 which is permanently secured to the underside of the deck and is 85 adapted to direct the sheaves delivered from the deck onto the lower end of the elevator.

As it is necessary in the operation of this machine that the elevator stop operating during the interval that the basket is dumping and then commence to operate when the basket is returned to the original position, I have provided a means for simultaneously controlling both the elevator and the basket, said means being operated from the binder. 95

On the shaft 76 I mount a free clutch member 91 and an opposing clutch member 92 which is feathered on the shaft and controlled by a lever 93 pivotally attached to the side bar 8. 100

A chain wheel 91' is formed integral with the clutch member 91 and is connected by means of a chain 91' with a chain wheel 94 located on the rear end of the pitman shaft 3. The details of the latter clutch members 105 are best shown in Fig. 11 of the drawings, where it will be seen that the clutch member 91 is rotatably mounted on a more or less spool-shaped sleeve 91° permanently secured to the shaft, the flanges of which prevent the 110 said clutch members from moving endwise on the shaft.

95 is a main controlling rod passing to any suitable location on the binder and within convenient range of the attendant 115 thereon. This rod is connected to one end of a bell crank 95' pivotally secured to the front bar 9 and one end of the bell crank is connected by means of an operating link 96 with the rear end of the lever 93. The other end of the bell crank is connected to a controlling rod 97 which passes across the front of the shocking machine and has the outer end thereof formed into an eye 97' which receives the downturned end 98' 120 of a forwardly directed, suitably supported rod 98 which has the rear end thereof carried by an inwardly extending arm 98' secured to the bearing 29. The rear end of the latter rod is supplied with a spanner 98° 125

which spans and controls the member 41 of the outer basket clutch.

99 is a further rearwardly directed rod corresponding to that 98, which rod has the 5 forward end thereof upturned as at 99' and entering an eye 97^x in the rod 97 and the rear end thereof mounted in a suitable bearing 99^x presented by the bearing 28. This rod also is provided with an upwardly directed spanner 99° which spans the inner clutch member at the inner side of the basket.

From the above arrangement it will be 15 obvious that upon the rod 95 being shifted to the left (see Fig. 1) the bell crank will effect, through the rod 96, the disengaging of the clutch members 91 and 92 and through the rod 97 and the rods 98 and 99 the engaging of the clutch members A and B of 20 the shocking machine. Accordingly, the elevator will go out of commission at the instant the basket clutches go into commission to turn the basket and vice versa.

"a" is a vertically disposed butting plate 25 located at the large end of the basket and pivotally mounted in hangers "b" disposed on the front end of the shocker frame.

"c" is a coiled spring connecting the upper part of the butting plate to the front 30 cross member 15 of the frame and "d" is a chain connecting the lower part of the butting plate with the latter cross member and limiting the inward turning of the lower side of the butting plate.

35 What I claim as my invention is:—

1. In a shocking machine the combination with a shocker frame, an open topped, normally horizontal disposed sheaf receiving and shock forming basket pivotally carried by the frame and means for turning the basket to dump, of a pair of normally upstanding and opposing compression arms pivotally secured to the opposite sides of the basket, horizontally disposed rotatably 40 mounted spindles carried by the sides of the basket, operating bars secured to the spindles and slidably connected with the upstanding ends of the compression arms, cam tracks suspended from the shocker frame at 45 the outer sides of the basket and levers permanently secured to the spindles and having their outer ends provided with rollers operating on the tracks.

2. In a shocking machine the combination 55 with a shocker frame, an open topped, normally horizontally disposed sheaf receiving and shock forming basket pivotally carried by the frame and means for turning the basket to dump, of a pair of normally upstanding and opposing compression arms pivotally and adjustably secured to the opposite sides of the basket, horizontally disposed rotatably mounted spindles carried by the sides of the basket, operating bars 60 adjustably secured to the spindles and slid-

ably connected with the upstanding ends of the compression arms, cam tracks suspended from the shocker frame at the outer sides of the basket and levers permanently secured to the spindles and having their outer ends provided with rollers operating on the tracks. 70

3. In a shocking machine the combination with a shocker frame, an open topped, normally horizontally disposed sheaf receiving and shock forming basket pivotally carried by the frame and means for turning the basket to dump, of a pair of normally upstanding and opposing compression arms pivotally and adjustably secured to the opposite sides of the basket and having their upper ends bent outwardly in a more or less semi-circular manner, horizontally disposed, rotatably mounted spindles carried by the sides of the basket, operating bars adjustably secured to the spindles and slidably connected with the upstanding ends of the compression arms and with the body portions thereof bent in a more or less S-shaped manner, cam tracks suspended from the shocker frame at the outer sides of the basket and levers permanently secured to the spindles and having their outer ends provided with rollers operating on the tracks. 75 80 85 90

4. In a shocking machine the combination with a shocker frame, an open topped, normally horizontally disposed sheaf receiving and shock forming basket pivotally carried by the frame and means for turning the basket to dump, of a pair of normally upstanding and opposing compression arms pivotally and adjustably secured to the opposite sides of the basket and having their upper ends bent outwardly in a more or less semi-circular manner, horizontally disposed, rotatably mounted spindles carried by the sides of the basket, operating bars adjustably secured to the spindles and slidably connected with the upstanding ends of the compression arms and with the body portions thereof bent in a more or less S-shaped manner, cam tracks suspended from the shocker frame at the outer sides of the basket and levers permanently secured to the spindles and having their outer ends provided with rollers operating on the tracks. 95 100 105 110 115

5. In a shocking machine the combination with a shocker frame, an open topped, normally horizontally disposed sheaf receiving and shock forming basket pivotally carried by the frame and means for turning the basket to dump, of piercing prongs extend- 120 125 130

ing normally through the bottom of the basket and means for withdrawing the prongs in the dumping of the basket.

6. In a shocking machine the combination 5 with a shocker frame, an open topped, normally horizontally disposed sheaf receiving and shock forming basket pivotally carried by the frame and means for turning the basket to dump, of a pair of rocker bars 10 pivotally secured to the underside of the basket, prongs projecting from the bars and protruding through and into the basket, springs normally projecting the prongs into the basket and means engageable with the 15 rocker bars in the turning of the basket to rock them and withdraw the prongs.

7. In a shocking machine the combination 20 with a shocker frame, an open topped, normally horizontally disposed sheaf receiving and shock forming basket pivotally carried by the frame and means for turning the basket to dump, of a pair of rocker bars 25 pivotally secured to the underside of the basket and having their lower ends fitted with prongs which project through and into the basket, springs interposed between the upper ends of the rocker bars and the body 30 of the basket and normally retaining the prongs projected into the basket and striking plates carried by the shocker frame and designed to hit the upper ends of the bars as the basket approaches dumping position and effect the withdrawal of the prongs.

8. In a shocking machine the combination 35 with a shocker frame, a sheaf receiving and shock forming basket pivotally mounted in the frame and means for turning the basket to dump, of cushioning means normally interposed between the basket and the frame and comprising spring cushioned striker 40 rods secured to the front end of the basket at opposite sides and engaging brackets secured to the frame.

9. In a shocking machine the combination 45 with a shocker frame, a sheaf receiving and shock forming basket pivotally mounted in the frame and means for turning the basket to dump, of cushioning means normally interposed between the basket and the frame and comprising spring boxes secured 50 permanently to the outer sides of the basket, rods slidably mounted in the boxes and with the ends thereof extending, collars mounted on the rods and within the boxes, springs interposed between the collars and the bases 55 of the boxes and brackets permanently secured to the sides of the frame and normally engaging with the upper ends of the rods in the normal receiving position of the basket.

Signed at Winnipeg, this 2nd day of 60
March, 1916.

HARRY GEORGE LANCASHIRE.
